US00D700908S

(12) **United States Design Patent**
Taniho et al.

(10) **Patent No.:** **US D700,908 S**
(b4) **Date of Patent:** **** Mar. 11, 2014**

(54) **SCANNER**

(71) Applicants: **Kiichi Taniho**, Kahoku (JP); **Yuusuke Kasashima**, Kahoku (JP); **Toshiki Satoji**, Milan (IT); **Alvise Gangarossa**, Milan (IT)

(72) Inventors: **Kiichi Taniho**, Kahoku (JP); **Yuusuke Kasashima**, Kahoku (JP); **Toshiki Satoji**, Milan (IT); **Alvise Gangarossa**, Milan (IT)

(73) Assignee: **PFU Limited**, Ishikawa (JP)

(**) Term: **14 Years**

(21) Appl. No.: **29/434,835**

(22) Filed: **Oct. 17, 2012**

(30) **Foreign Application Priority Data**

Sep. 27, 2012 (JP) 2012-023491

(51) LOC (10) Cl. **14-02**

(52) U.S. Cl.

USPC **D14/422**

(58) **Field of Classification Search**

USPC D14/420-425, 462-470, 389, 125, 399; D18/50, 54, 55, 53, 36-39, 14, 18-21, D18/49, 52, 51, 54.4; 358/400, 401, 448, 358/474, 486-488, 496; 382/312, 317, 321, 382/315; 400/613, 613.1-613.4, 400/690.1-690.4, 691-694, 88, 175; 399/107, 379, 380, 211, 212; 235/462.11, 462.41, 472.01, 470, 235/462.43; 361/680, 681

See application file for complete search history.

(57) **CLAIM**

The ornamental design for a scanner, as shown and described.

DESCRIPTION

FIG. 1 is a front perspective view of a scanner showing our new design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

Broken lines and unshaded portions contained within broken line are not claimed.

1 Claim, 4 Drawing Sheets
